UNITED STATES PATENT OFFICE.

PHILIP M. KIRKLAND, OF INDEPENDENCE, OREGON.

COLLAPSIBLE CAMP-TABLE.

1,262,356.

Specification of Letters Patent.

Patented Apr. 9, 1918.

Application filed August 21, 1917. Serial No. 187,335.

To all whom it may concern:

Be it known that I, PHILIP M. KIRKLAND, a citizen of the United States, residing at Independence, in the county of Polk and 5 State of Oregon, have invented certain new and useful Improvements in Collapsible Camp-Tables; and I do hereby declare the following to be a full, clear, and exact description of the invention, such as will enable others skilled in the art to which it 10 appertains to make and use the same.

The present invention relates to tables, and more particularly to that type known as folding tables.

15 An object of the present invention is to provide a collapsible camp table which may be quickly and easily folded into compact form and packed in a relatively small space; which is light in weight, simple construction, is strong and rigid when set up, and 20 has relatively few parts; and a table which may be economically constructed.

The above, and various other objects and 25 advantages of this invention will be in part described, and in part understood, from the following detailed description of the present preferred embodiment, the same illustrated in the accompanying drawings, wherein—

Figure 1 is a perspective view of a folding camp table constructed according to 30 the present invention, the same being set up, and the top being shown in dotted lines.

Fig. 2 is a plan view of the table top. 35 Fig. 3 is a transverse section through the same in the plane of the hinges.

Fig. 4 is a fragmentary perspective view 40 of the interlocking end portions of the members of the table at one corner thereof, the end portions being shown separated.

Fig. 5 is a fragmentary sectional view 45 of the end portions of Fig. 4 in assembled relation.

Referring to this drawing, 10 designates 50 a central post or leg which is preferably rectangular in cross section to present a plurality of flat faces at the opposite sides of the post 10. The post 10 is provided with a plurality of legs 11 which are pivotally mounted intermediate their ends on 55 bolts 12 which pass through post 10 and hold the intermediate portions of the legs 11 flat against the adjacent sides of the post 10. The post 10 is preferably provided with four flat sides and a leg 11 is provided

for each flat side of the post. The four legs 11 are adapted to be swung about their bolts or pivots 12 into substantially parallelism with the post 10 to fold the pedestal structure of the table into compact form. 60

As shown in Fig. 1, the legs 11 may be swung into positions obliquely across the adjacent faces of the post 10, in which positions the legs 11 diverge downwardly and are substantially supported by the post 65 10. The legs 11 are of a length such that their lower ends lie substantially in the same horizontally plane of the lower end of the post 10. The legs 11 are preferably reinforced at the portions through which 70 the bolts 12 engage by sheet metal straps 13 which may extend about three sides of the legs 11 and are suitably apertured to receive the bolts 12 therethrough.

Two adjacent legs 11 are provided with 75 extension feet 14 in the form of flat bars slidably engaging against the lower edges of the legs 11, at their lower ends. The extensions 14 are held against the inner edges of the legs 11 by metal straps 15 80 suitably secured to the legs and engaging about the extensions, a pair of metal straps being preferably arranged upon each of the two legs. Set screws 16 are threaded through the legs 11 opposite the extensions 85 14, and are adapted to bind against the latter for holding them in longitudinally adjusted position in the metal straps 15. The extensions 14 are adapted particularly for use where the camp table is set up on the 90 side of a terrace, or on uneven ground, and wherein it is necessary to lengthen one or more of the legs for maintaining the top of the table in substantially a horizontal plane.

The upper end of each leg 11 is provided 95 with a sheet metal cap 17, the latter inclosing the upper end of the leg 11 and being riveted or otherwise permanently secured thereto. Locking pins are screwed into the upper ends of the legs 11 and the caps 17, 100 the pins 18 projecting upwardly and substantially vertically, and the upper ends of the legs being beveled to lie substantially in a horizontal plane, when the legs are set up or spread apart.

A pair of pivotally connected cross-braces 19 are adapted to be placed in crossed relation at their intermediate portions upon the upper end of the post 10, the braces 19 having registering apertures adapted to receive 110

therethrough an upstanding threaded stem 20 projecting from the top of the post 10 to hold the braces from relative longitudinal movement, and from displacement from the post. The stem 20 is provided with a nut threaded on its upper end and which is adapted to be advanced or screwed against the braces 19 to hold them to the post and securely lock all the parts in set up position.

Each end of each brace 19 is reinforced by the provision of a metal cap or plate 21, which is riveted or otherwise suitably secured to the end of the brace, and which is provided in opposite sides with longitudinally extending slots 22, the slots registering and extending through the adjacent ends of the brace 19. The slots 22 are of a width to freely receive the upstanding locking pins 18 therethrough, the pins 18 being adapted to be inserted at any suitable point in the slots 22, and to move into the outer ends of the slots to engage the marginal edges of the caps 21 and the braces 19 to hold the upper ends of the legs 11 from spreading beyond the ends of the braces. These braces 19 reinforce and hold the legs from spreading, impart to the table pedestal structure relatively great strength, and provide means which may be quickly disengaged from the legs and the central post and folded into compact form for packing into a small space with the legs.

A pair of side bars 23 is provided, the bars 23 having near their opposite ends apertures 24 therethrough for the reception of the pins 18, which latter project upwardly through the braces 19 and may project through the bars 23 to hold the same in substantially parallel relation at the opposite sides of the table structure.

The side bars 23 have flat upper faces adapted to receive a top 25 thereon, the top being preferably formed of a plurality of hinged leaves or sections which may be collapsed into small space.

When the table is set up, as shown in Fig. 1, the lower edges of the legs 11 engage across the upper edges of the next adjacent legs extending therethereunder so that the legs are interlocked and pressed against each other to a large extent, and by the provision of the braces 19, the legs and the posts form a substantially rigid strong structure capable of withstanding an extra amount of weight and hard usage.

The device is adapted particularly for picnic, camp parties and the like, and may be conveniently packed in an automobile, a boat, or other convenient place of transportation, and occupies but relatively small space. It will be noted that not only may the leg structure be folded compactly, but the brace bars 19 and the side bars 23 may also be folded compactly and strapped or

otherwise suitably secured against the leg structure.

While the present embodiment of the invention as disclosed in the accompanying drawing is designed to be made from wood, it is of course understood that the parts may be constructed from sheet metal or the like, without departing from the spirit of the invention.

The top 25 is provided with recesses or openings 26 in its under side adapted to register with the locking pins 18 and receive the upper ends of the pins therein. The locking pins 18 thus retain the braces, and the side bars, and may retain the top in assembled relation on the upper ends of the legs.

The table top 25 may be formed of any desired number of sections, and for the purpose of illustration the table top is shown in the present instance as having four sections or leaves. The middle sections are hingedly connected together at their upper adjacent edges and the next adjacent sections are hingedly connected at their lower edges to the free ends, and to the lower edges, of the intermediate sections. It is of course understood that where more than four leaves or sections are employed, the hinges connecting the sections are alternately arranged at the upper and lower meeting edges of the sections so that the latter may fold oppositely and successively upon one another.

The central post 10 is preferably of such length that when the cross-pieces 19 are connected to the upper ends of the legs, the lower end of the post 10 is spaced from the ground so that the upper ends of the legs bind in the ends of the cross-pieces and thus firmly connect the parts and hold them from vibration. In this instance, the central post 10 forms a connection between the legs and the braces.

What is claimed is:

1. In a folding table, a central post, legs pivoted intermediate their ends to the opposite sides of the post and adapted to be swung diagonally across the post to support the same, locking pins extending upwardly from the upper ends of the legs, braces detachably engaging across the post and the legs and having openings in their ends to receive the locking pins, side bars engaging across the ends of the braces and having openings therein to receive the locking pins, and a collapsible top resting on said side bars.

2. In a folding table, the combination of a central post, a plurality of legs pivoted intermediate their ends to the opposite sides of the post and adapted to be swung into open position about the post, a pair of braces detachably engaging in crossed relation upon the upper end of the post, means for

detachably interlocking the upper ends of the legs to the outer ends of the braces, and a table top detachably supported upon the braces.

5 3. In a folding table, the combination of a central post, a plurality of legs pivoted intermediate their ends to the opposite sides of the post and adapted to be swung into open position thereabout, a pair of brace bars having apertures intermediate their ends, a stem projecting upwardly from the post for engagement through the apertures in the brace bars to retain the latter in crossed relation on the upper end of the post, 10 side bars engaging over the ends of the brace bars, a collapsible top resting on said side bars, and locking means carried by the legs for detachable engagement with the adjacent portions of the brace bars, the side bars 15 and the top.

4. In a folding table, the combination of a central post, a plurality of legs pivoted intermediate their ends to the opposite sides of the post and adapted to be swung into

open position thereabout, extensions slidably mounted on an adjacent pair of the legs, for securing the table upright on an inclined surface, a pair of brace bars detachably secured in crossed relation upon the upper end of the post and having longitudinally extending slots near the outer ends, pins extending upwardly from the upper ends of the legs and adapted to engage in said slots to hold the legs to the braces, side bars engaging across the braces and having 25 openings therein for the reception of said pins to retain the side bars on the braces, and a collapsible top resting on said side bars and having openings in its under side 30 to receive the upper extremities of said pins 35 for anchoring the top to the table.

In testimony whereof I affix my signature in presence of two witnesses.

PHILIP M. KIRKLAND.
